SPINNING CENTRIFUGE

Robert Kalkbrenner, Breslau, and Hermann Toebl, Wuppertal-Elberfeld, Germany, assignors to North American Rayon Corporation, New York, N. Y., a corporation of Delaware

Application December 20, 1932, Serial No. 648,026
In Germany December 21, 1931

4 Claims. (Cl. 18—8)

Our present invention relates to improvements in centrifugal spinning machines used in the manufacturing of artificial silk, threads, filaments and the like and more particularly to a method of and apparatus for the regulation of the speed of the thread guide which is used to lead the said threads, filaments and the like to the spinning pot.

In the use of centrifugal spinning apparatus, the thread, after being coagulated in a suitable spinning bath, is guided over a take-up roller and into a rapidly rotating pot. The thread collected in this manner is gradually built up in the form of a "spinning cake". The thread guides generally consist of a tubular member through which the thread passes and to which a reciprocating motion is imparted.

Such method of forming and collecting of artificial threads, silk, filaments and the like, although for the most part satisfactory, has been found to result in the production of a rather poor thread cake due primarily to the fact that since the different thread layers are placed quite uniformly, either one on top of the other or side by side, there is a great tendency for the thread to form impervious sections throughout the cake body. These impervious sections are detrimental to the wet after-treatment and rewinding of the thread into yarn packages and the like.

It is, therefore, one object of our present invention to provide an improved apparatus for guiding the formed thread into the spinning cakes so that the thread crossings of the different layers of the cake as it is built up will not be placed either one on the other or side by side.

Another object of our present invention is to provide an improved mechanism for reciprocating, in pot spinning mechanisms, the thread guide, whereby the speed of the reciprocation thereof may be either retarded or accelerated during the building up of the spinning cake so that the thread crossings of different layers will not be placed one on the other. Such method of building up the cake body will prevent the formation of matte-like sections which, being impervious to the liquids of the cake, will prevent satisfactory wet after-treatment thereof.

A still further object of our present invention is to provide an improved mechanism which will vary the rotation of the shaft by which the thread guide is reciprocated; such change in rotation varying the speed of reciprocation of the thread guide to such an extent as to prevent the formation of uniform thread crossings in the thread body.

These and other features of our present invention will become more apparent from a study of the following description in connection with the attached drawing, in which:

Fig. 1 is a semi-diagrammatic view in side elevation of a form of the invention, as used in conjunction with the pot spinning mechanism;

Figure 2 is a sectional view of the driving apparatus disclosed in Figure 1; and

Figure 3 is a sectional detail view taken along the lines 3—3 of Figure 2.

Referring now to the drawing it will be found that like numerals of reference indicate like parts. As shown in the drawing the thread is led into the spinning pot 19' by means of a thread guide tube 10' secured to the holder 11'. The thread guide holder is secured to a rail 12' to which is pivotally attached lever 15' pivotally connected to its upper end to a bell crank 15' carrying a roller 16' contacting with a cam 13' secured to a cam drive shaft 14'.

Reciprocating motion is imparted to the rail 12' and hence to the thread guide tube 10' by means of the cam 13' mounted on the shaft 14' and rotated thereby. The rail 12' is operatively connected with the cam 13' through the bell crank 15' carrying a roller 16' which rides against the said cam 13', the other end of the bell crank lever 15' being pivotally connected to the level 16a' which in turn is pivotally attached to the rail 12'.

In normal operation the rotation of the cam 13' will impart to the thread guide tube 10' a reciprocating motion which is maintained constant throughout the building up of the spinning cake 35 within the spinning pot.

However, in the invention of applicants the speed of reciprocation of the thread guide tube 10' is varied by means of a novel differential gearing arrangement hereinafter more fully described.

The mechanism embodied to rotate the cam shaft comprises a driving gear 28 secured to a sleeve 29, rotatably mounted on the cam drive shaft. Referring now to Figures 2 and 3, we have shown in detail the construction of the differential for either accelerating or decreasing the speed of rotation of the cam shaft. Gears 28, 31 and 32 are mounted on a sleeve 29 which is rotatably mounted on the cam shaft and are connected with the disk 34 also secured to the cam shaft by means of a slide 35. The slide 35 has secured thereto a bolt 36 carrying a roller 37 positioned in an eccentrically disposed groove formed in gear 31. As will be noted from an 55

inspection of the drawing, gear 31 is loosely mounted on the sleeve 33.

The lower end of the slide is likewise provided with a bolt 38 carrying a roller 39 which rides in a slot 40 formed in the disk 34. Gears 31 and 32 are connected to each other by intermediate gears 41 and 42 of different size.

In operation, gear 28 is driven by any suitable source of power thereby rotating sleeve 29 and gear 32. This rotation is imparted to gear 31 through the intermediate gears 41 and 42. The rotation of gear 31 imparts an up and down motion to slide 35 through the bolt 36. Since the slide is also connected to the disk 34 by the bolt 38 residing in the slot 40, the said disk will be rotated but, however, at a varying speed due to the position of the slot 40 which, allowing a sliding action of the roller in the slot, will vary the speed of rotation of the disk and hence change the speed of rotation of the cam shaft.

From the above description it will be appreciated that we have provided a simple and efficient method of and apparatus for building up spinning cakes which are free from impervious sections therein, heretofore found to be frequently present in spinning cakes and which detrimentally affect the after-treatment and re-winding thereof.

Having now described the invention, what we claim as new is:

1. In a centrifugal spinning machine, a spinning pot, a thread guide for leading thread into said pot, a drive for said thread guide comprising a shaft, a cam secured thereto, means operatively connecting said thread guide to said cam whereby upon rotation of said shaft reciprocatory movement is imparted to said thread guide, and means for varying the speed of rotation of said shaft comprising a slide, a disk se-

cured to said shaft, means to move said slide, said disk being provided with a slot in which is slidably secured means carried by said slide for rotating said slide at variable speeds.

2. In a centrifugal spinning machine, a spinning pot, a thread guide for leading thread into said pot, means to reciprocate said thread guide and means to vary the speed of reciprocation of said thread guide including, a drive shaft, a disk secured to said shaft, a slide in operative engagement with said disk, means to move said slide, said disk being provided with a slot in which is slidably secured means carried by said slide for rotating said slide at variable speeds.

3. In a centrifugal spinning machine, a spinning pot, a thread guide for leading thread into said pot, means to reciprocate said thread guide, and means for varying the speed of reciprocation of said thread guide comprising a drive shaft, a disk secured to said shaft, a sleeve rotatably mounted on said shaft, differential gearing mounted on said sleeve, a slide operated by said differential gearing, said slide having means secured thereto for riding in a slot in said disk for rotating said disk at variable speeds.

4. In a centrifugal spinning machine, a spinning pot, a thread guide for leading thread into said pot, means to reciprocate said thread guide, and means for varying the speed of reciprocation of said thread guide comprising a drive shaft, a disk secured to said shaft, a sleeve rotatably mounted on said shaft, differential gearing mounted on said sleeve, a slide revolved and reciprocated by said differential gearing, said slide having means secured thereto for riding in an eccentric slot in said disk whereby said disk is rotated at varying speeds.

ROBERT KALKBRENNER.
